(57) **CLAIM**

The ornamental design for a portable grill, as shown and described.

DESCRIPTION

FIG. 1 is a perspective view of a portable grill.
FIG. 2 is a front view of the portable grill of FIG. 1.
FIG. 3 is a rear view of the portable grill of FIG. 1.
FIG. 4 is a right side view of the portable grill of FIG. 1.
FIG. 5 is a left side view of the portable grill of FIG. 1.
FIG. 6 is a top view of the portable grill of FIG. 1; and,
FIG. 7 is a bottom view of the portable grill of FIG. 1.
The features shown in broken lines form no part of the claimed design.

The lighter solid lines denote surfaces and contours. Line shading is not surface ornamentation.

1 Claim, 7 Drawing Sheets
